Primary Examiner — Darlington Ly(74) *Attorney, Agent, or Firm* — Global IP Counselors, LLP(57) **CLAIM**

The ornamental design for a rear bumper for automobile, as shown and described.

DESCRIPTION

FIG. 1 is a front elevation view of a rear bumper for automobile showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front, top, and right side perspective view thereof; and,

FIG. 7 is a front, bottom, and left side perspective view thereof.

The rear surfaces of the rear bumper for automobile shown in the figures as darkened areas forms no part of the claimed design.

1 Claim, 7 Drawing Sheets(56)
